The ornamental design for a multiwell plate, as shown and described.

DESCRIPTION

FIG. 1 is a perspective view of a multiwell plate in accordance with the present invention showing the new design, said multiwell plate including 96 wells (A1, A2, A3 etc.), each being subdivided into four compartments by subdividers to provide 384 separate reservoirs for liquid samples.

FIG. 2 is an enlarged perspective view of a portion of the top of the multiwell plate of FIG. 1, which shows details of several wells and their respective subdividers.

FIG. 3 is a top view of the multiwell plate of FIG. 1.

FIG. 4 is a front view of the multiwell plate of FIG. 1.

FIG. 5 is a rear view of the multiwell plate of FIG. 1.

FIG. 6 is a left side view of the multiwell plate of FIG. 1.

FIG. 7 is a right side view of the multiwell plate of FIG. 1; and, FIG. 8 is a bottom view of the multiwell plate of FIG. 1 showing only the perimeter edge thereof, no claim being made to the bottom side thereof.
